UNITED STATES PATENT OFFICE.

MICHAEL SWEENEY, OF WHEELING, WEST VIRGINIA, ASSIGNOR TO SWEENEY, BELL & CO., OF SAME PLACE.

IMPROVED LANTERN-GLOBE.

Specification forming part of Letters Patent No. **96,053**, dated October 19, 1869.

To all whom it may concern:

Be it known that I, MICHAEL SWEENEY, of Wheeling, in the county of Ohio and State of West Virginia, have invented a new and useful Improvement in Lantern-Globes; and I do hereby declare that the following is a full, clear, and exact description thereof, reference being had to the annexed drawings, making part of this specification, in which—

Figure 1 is an elevation. Fig. 2 is a vertical section. Figs. 3, 4, and 5 are transverse sections in different portions of the globe.

This invention relates to lantern-globes; and my improvement consists in constructing such globes with lenses or reflectors concavo-convex in form and blown in the globes while in process of formation, and so that the walls of the globes shall be of uniform thickness, or nearly so.

A in the drawings represents the seat, or that part of a lantern-globe which rests on the base of the lantern, from which part extends the body B, which terminates in the mouth C.

The lower portion of the body B is enlarged in the ordinary manner, and in this part I propose to form concavo-convex reflectors, of which I have shown four in the drawings,

which, by reflection and refraction, aid in the diffusion of the light of the flame, and at the same time give an ornamental and pleasing appearance to the globe. These reflectors are to be formed in the globes while being blown, and at such points therein that their centers will be about in line with the flame, care being taken to prepare the molds for this purpose in such a manner that the glass shall be made of uniform thickness, or as nearly so as possible, in all parts of the globe.

Having thus described my invention, what I claim, and desire to secure by Letters Patent, is—

As a new article of manufacture, a glass lantern-globe constructed with four (more or less) concavo-convex reflectors, said reflectors being blown in the globe while being formed, substantially as set forth.

In testimony whereof I have signed my name to this specification in the presence of two subscribing witnesses.

MICHAEL SWEENEY.
